Darby & Darby

Patented July 5, 1927.

UNITED STATES PATENT OFFICE.

BRUNO O. A. DE PAOLI, OF PALISADE, NEW JERSEY.

TERRAZZO FLOORING.

Application filed October 17, 1921. Serial No. 508,903.

This invention relates to terrazzo flooring.

The object of the invention is to provide a construction of terrazzo or crushed marble flooring which is simple, efficient and 5 economical.

A further object of the invention is to provide a flooring of the character referred to wherein provision is made for avoiding cracks or openings resulting from expansion 10 and contraction of the flooring composition, or the floor supporting or other parts of the building in which the flooring is employed.

A further object of the invention is to provide a flooring of the character referred to 15 wherein expansion joints are provided in the flooring composition in the wearing surface of the floor, and the adjacent edges of the joint are efficiently protected against "spalling" or other injury.

20 Other objects of the invention will appear more fully hereinafter.

The invention consists substantially in the construction, combination, location, and relative arrangement of parts, all as will be 25 more fully hereinafter set forth, as shown in the accompanying drawing, and finally pointed out in the appended claims.

Referring to the accompanying drawing,

30 Fig. 1 is a view partly in perspective, parts broken off, showing a terrazzo flooring constructed in accordance with the principles of my invention.

Fig. 2 is a broken view in perspective 35 showing forms of joint protecting strips employed for protecting the edges of the sections of the flooring at a joint therein, said strips being shown separated from each other.

40 Fig. 3 is a broken view in top plan showing a portion of a pair of joint protecting strips applied together in position for use.

Figs. 4, 5 and 6 are broken detail views in side elevation showing various arrangements 45 and forms of anchoring devices for the joint protecting strips employed in accordance with my invention.

Fig. 7 is a detail view showing the manner of forming the protecting strips employed in connection with my invention.

It is at present a common practice in laying terrazzo floors to employ a foundation layer of suitable material or composition which is placed upon the floor supporting 55 girders or beams of the building. This

foundation material is commonly composed of a mixture of cement and cinders in suitable proportions. In practice, a composition consisting of one part of cement to six of cinders has been found suitable. This 60 foundation layer or composition is applied to the floor supports to any desired depth or thickness, according to the requirements. In practice, this depth or thickness may run from five or less inches to ten or more, as 65 may be desired. Upon the foundation composition layer is then imposed a layer of material called the levelling or scratch coat, which, ordinarily, is composed of sand and cement in suitable proportions. A sand and 70 cement composition consisting of one part of cement to three or four parts of sand has been found satisfactory for use as a levelling or scratch coat. This layer of composition may vary in thickness, and ordinarily a 75 thickness of three-quarters of an inch is found satisfactory. The purpose of the levelling coat or layer is to attain and fix the desired standard of level of the surface of the floor when finished. Upon the levelling or scratch coat the terrazzo or crushed marble and cement composition is placed and levelled off to form the floor surface. To 80 economize in the quantity of marble constituent of this terrazzo composition, which is 85 expensive, it is customary to first place upon the levelling or scratch coat a layer of grit and cement in the proportion of one part of cement to two or three parts of grit, more or less, and upon this filling layer the 90 crushed marble or terrazzo and cement composition, ordinarily in the proportion of one part of cement to two of the crushed marble is placed, and to the desired depth or thickness, according to requirements. 95

Floors constructed in this manner are subjected to the strains and stresses due to expansion and contraction of the various compositions employed as well as to the expansion and contraction of the steel framework of the floor supports or of the building, and such expansion and contraction frequently causes the composition flooring to crack, and ordinarily when cracks or crevices develop in the surface of the flooring they 100 are irregular in shape and in line of cleavage of the floor surface. It is a difficult and expensive matter to repair such a crack when it develops, and by reason of the irregularity 105 of outline and of direction of trend there- 110

of, a repaired crack or crevice leaves an unsightly patchwork appearance however carefully the repair may be effected.

It has been attempted to overcome this objection by laying out the floor surface in panels. In carrying out this idea the floor area is laid out in a regular panel scheme by the use of suitable strips. The panel areas thus formed are then filled in with the terrazzo cement surface composition. According to this method the panel areas are filled separately, alternate panels in adjacent rows being filled successively and left to become set or hardened, usually for a day's time, and then the panel strips are removed and the alternate intermediate panel areas are then filled. This method is expensive and slow, and moreover, in case of expansion and contraction above referred to, the seams left by the panel strips between adjacent rows of panels or between adjacent panels, tend to separate from each other, and too, the edges of the panels at the seam become broken off or "spalled", leaving a rough irregular line of opening between adjacent panels which is unsightly and unsatisfactory, and when such seams open up or "spall" off sufficiently to require repair by grouting or otherwise, it leaves an unsightly irregular patchwork appearance, which is exceedingly objectionable.

It has also been proposed to employ metal strips which are imbedded into the floor composition at the time it is laid in order to form a permanent metallic retaining wall for the edges of adjacent panels of the floor, thereby forming expansion joints along which may follow any crack which might be developed in case of contraction or expansion.

According to such practice however, it is usual to employ a single strip between adjacent panels or for each expansion joint. This, however, does not overcome the objections above noted, for the reason that in case the joint should open up the strip will remain in contact with the surface adjacent one panel, and leave a space between the strip and the adjacent wall or surface of the crack of the other panel, thereby rendering the separated wall liable to spalling or cracking off along its unprotected edge.

It is among the special purposes of my invention to provide a structure and arrangement of protecting strips which overcomes the objections above noted, and which will afford protection for the approximate edges of both adjacent panels on opposite sides of a seam or joint. I have found that in providing the protecting strips of the nature and character suggested that it is necessary not only to efficiently anchor the same in the composition body composing the floor structure, but also that it is necessary to anchor and support each strip with particular ref-

erence not only to the floor composition as a whole, but with reference to the portion or panel of floor surface which each strip is designed to protect against injury at a joint. To accomplish this, in carrying out my invention, generally stated, I propose to employ at each joint a pair of strips having laterally extending base flanges to anchor them in the flooring composition, and having vertical web portions lying flatwise against each other and extending to the flooring surface, to afford protection against "spalling" or breaking off of the edges of the floor paneling at the joints thereby formed therein, and, in addition, I provide each protecting strip with lugs or tongues pressed out of the vertically extending web portion of each strip to form anchoring or supporting means within the body of the flooring composition or the panel portion thereof, which said strip is to protect at the edge of the joint. In this manner I not only primarily anchor each strip within the body of the composition of the flooring, but I also efficiently anchor each strip in the body of the particular panel, the edge of which is to be protected thereby, thus insuring against the danger of the protecting strip becoming displaced away from the edge or surface of the joint to be protected thereby.

In the accompanying drawing I have shown various arrangements embodying the principles of my invention. Referring particularly to Fig. 1, I have illustrated a terrazzo flooring arrangement of suitable flooring compositions such as are commonly employed consisting of a base material 12, upon which a levelling coat, or scratch coat, or layer, is placed. 14 designates the filler layer of composition material which is placed upon the levelling coat 13, and 15 designates the terrazzo composition which constitutes the top layer of the composition flooring, and contains the expensive crushed marble particles to form the wearing surface, together with the surface appearance of the finished floor. As above indicated, in laying the composition flooring, the base composition 12 is first laid down, and then the levelling or scratch coat 13 is applied thereto, and is levelled off and left to harden. Before applying the layer of filler material or composition 14 the metal strips to form joints and protectors for the edges of the resulting panels or portions of the surface layers of composition are positioned in place upon the surface of the scratch coat or levelling coat. This is a convenient arrangement and manner of application of the strips, but in its broadest scope my invention is not to be limited in this respect. After the plates are positioned in place the filler layer 14 is applied and then the surface layer of terrazzo composition 15 is finally applied, and the entire flooring sur-

face is then ground or smoothed off to complete the work to finish the floor. In accordance with my invention I provide at each joint a pair of strips indicated generally at 16, 17, in Figs. 1 and 2. Each strip is formed with a laterally extending flange 18 at its lower edge, and with a vertically extending web portion 19. In assembling the strips in place the vertical web portions 19 thereof are placed flatwise against each other while the laterally extending flanges 18 project in opposite directions away from each other. In practice, the laterally extending base flanges 18 constitute anchorages for the strips, these flanges being embedded within the body of the composition of the flooring. Where the strips are positioned in place upon the surface of the scratch coat or levelling coat 13, said flanges 19 rest upon said surface and become anchored thereto by the application of the filler layer 14 and the terrazzo layer 15 of the flooring composition. The upper edges of the vertical web portions 19 of the strips extend to the wearing surface of the terrazzo flooring layer 15, and hence not only form expansion joints between adjacent panels or portions of the flooring composition to accommodate any expansion or contraction in the composition or in the floor supporting structure or of the building structure in which the flooring is placed, but also protecting the edges of the joint between such adjacent panels or portions of the flooring composition, each strip forming an edge protector for the respective approximate walls and edges of the adjacent panel portions of the flooring. It is also clear that these strips form guides to correctly determine the depth of the terrazzo flooring. In order to firmly anchor the vertical web portion of each strip with reference to the panel or portion of the floor surface, which said strip is designed to protect at the expansion joint, I propose to provide each strip with suitable tongues or projections pressed out from the web portions of the strip so as to become imbedded in the composition of the wall at the point at which it is to be protected. These auxiliary anchorage lips or projecting portions are indicated at 20, and are formed by suitably slitting the vertical web portions of the strips, and then pressing or bending outwardly away from the planes of such web portions the resulting tongues. These tongues may be of any suitable or desired shape or outline, and in Figs. 4, 5 and 6 I have shown various outlines or configurations which may be employed. In practice, the anchoring tongues 20 formed in the web portion of strip 17 are in staggered or alternate relation with respect to the tongues 20 formed in the adjacent and cooperating strip 16. I also prefer to form the slits for producing the tongues in the direction 65 of the general longitudinal dimension or length of the strips. These tongues may be bent out from the planes of the web portions of the strips to any desired angle. Ordinarily they will be bent out into an angle of 70 less than a right angle, as indicated in Fig. 3. It will be observed that the anchoring tongues of each strip are bent out from the plane of the web portion of the strip and in the same direction with respect to the web 75 portion as the anchoring base flange 18 thereof, and hence it will be seen that the anchoring tongues of each strip will become imbedded within the body of the composition forming the panel or portion of the 80 floor to the wall of the joint of which the vertical web portion of the strip is applied, and hence when the joint between the two protecting strips or between adjacent panels or portions of the flooring opens up under 85 the action of expansion or contraction each wall and edge of the joint will retain its own protecting strip, and said edges will be protected against the danger of spalling or of breaking off of particles of the terrazzo 90 flooring composition. Thus I am enabled to avoid the danger of injuring or disfiguring the symmetrical paneled effect of the floor surface through unsightly cracks or 95 seams or through spalling or breaking off of the edges, one or the other, or both, of adjacent portions of the floor surface at the joints, each protecting strip being firmly anchored not only to the base composition of 100 the flooring, but also to the panel portion 105 which is to be protected thereby, and each strip is held to its anchorage against the danger of being separated therefrom. In practice I prefer to initially form the two strips in one piece with each other as indicated in Fig. 7 by suitably bending a sheet of metal into loop shape to form the base flanges 18 and vertical web portions 19 with the anchoring tongues 20, the two portions 110 of the strip being connected at the medial bend indicated at 22. This compound strip structure is then positioned in place as above described, and the flooring composition layers applied as above set forth. In the operation of smoothing off the wearing surface 115 of the floor the connecting portion 22 between the strips is ground off, leaving the two strips separated and independent of each other. This insures the efficient and proper positioning or anchoring of the compound strip before the two portions thereof are separated from each other, and avoids the necessity for separately handling two different strips in positioning and anchoring 120 the same.

Having now set forth the objects and nature of my invention, and a structure embodying the principles thereof, what I claim

as new and useful and of my own invention and desire to secure by Letters Patent is,—

1. In a terrazzo flooring construction provided with a base composition upon which the terrazzo flooring composition is spread metal strips or plates having vertically extending web portions disposed flatwise against each other and having laterally extending anchoring flanges at their lower portions, said anchoring flanges extending in opposite directions away from each other, the vertically extending web portions of said strips having tongues pressed out therefrom, the tongues of one strip being in longitudinal staggered relation with respect to the tongues of the other strip, said strips being placed on said base composition and acting as a depth guide for the terrazzo flooring composition.
2. In a terrazzo flooring construction provided with a base composition upon which

the terrazzo flooring composition is spread metal strips or plates having vertically extending web portions disposed flatwise against each other and having laterally extending anchoring flanges at their lower portions, said anchoring flanges extending in opposite directions away from each other, the vertically extending web portions of said strips having tongues pressed out therefrom, at points remote from the edges of the strips, the tongues of one strip being in longitudinal staggered relation with respect to the tongues of the other strip, said strips being placed on said base composition and acting as a depth guide for the terrazzo flooring composition, and said strips being joined at their web portions.

In testimony whereof I have hereunto set my hand on this 8th day of October A. D., 1921.

BRUNO O. A. DE PAOLI.
